UNITED STATES PATENT OFFICE.

FRED G. STONE, OF MANCHESTER, NEW HAMPSHIRE, ASSIGNOR TO STONE SURFACE WASHER COMPANY, INC., OF NORTH ANDOVER, MASSACHUSETTS, A CORPORATION OF MASSACHUSETTS.

SURFACE WASHER.

Application filed September 21, 1925. Serial No. 57,622.

This application is a continuation in part of my application for Letters Patent for an improvement in surface washers, filed June 4, 1925, Serial No. 34,817.

5 One object of this invention is to provide a device, adapted to be held by one of the hands of the user, and including a water-conducting receiving head having a water-delivering rose head against which a detached applicator, such as a sponge, may be releasably confined by the operating hand, for manipulation on a surface to be washed, the applicator being supplied with water by the rose head, and a water-conducting neck 15 connecting the heads and formed to bear on fingers of an operating hand, the arrangement being such that the receiving head is offset inwardly from flexed fingers of the operating hand, and is free from liability to have injurious contact with a surface portion of a body being washed.

Another object is to enable the water-receiving head to project a stream of water over the back of the operating hand, without contact with the latter, and cause the jet to impinge directly on a portion of the surface being washed, at a point near the portion of a surface portion to which the applicator is applied.

20 Other objects will appear as the description proceeds.

Of the accompanying drawings forming a part of this specification,—

Figure 1 is a side view, showing a washer embodying the invention, and an applicator associated therewith, the washer and applicator being held by an operating hand in operative relation to a surface to be washed.

Figure 2 is an end view, omitting the applicator.

Figure 3 is a section on line 3—3 of Figure 2.

Figure 4 is a section on line 4—4 of Figure 3.

Figure 5 is a view similar to Figure 3, omitting the water-delivering nozzle portion hereinafter described of the receiving head.

Figure 6 is a perspective view, showing a modification.

Figure 7 shows in elevation the modification shown by Figure 6.

Figure 8 is a view similar to Figure 1, showing a differently formed connecting neck.

Figure 9 is an end view, showing the neck 85 formed as in Figure 8.

The same reference characters indicate the same parts in all of the figures.

12 designates a water-receiving head having means for connection with a source of water supply, said means preferably including a nipple 13, adapted to engage a flexible hose 14. The head 12 is preferably provided with a nipple portion 15, closed at its outer end and provided with an outlet 16, adapted to deliver a fan-shaped jet 17, and cause its impingement on a surface 18 to be washed.

Extending laterally from the head is a water-conducting neck, formed to bear on fingers 19 of an operating hand. Said neck 70 preferably includes an annular body member 20, integral with the head and provided with an annular groove 21, and a separately formed annular groove-closing member 22, having a water-tight connection, formed by solder or otherwise, with the body member, said groove and closing member forming an annular duct extending through the neck and communicating by a passage 23, with the bore of the head 12, as shown by Figure 3.

The body portion 20 has a finger-receiving opening 24, and its wall is preferably oblong in cross section and tapered as shown by Figure 4, so that it is adapted to conform to the diverging spaces between the fingers.

85 A water-delivering rose head is carried by the neck and is spaced thereby from the head, so that the fingers may be interposed between the head and the nozzle. In this embodiment of the invention the rose head includes a discoidal inner member 25, integral with the neck and communicating with the neck duct by a passage 26, and a separately formed discoidal water-delivering outer member 27, having a water-tight connection with the member 25, formed by solder or otherwise. The members 25 and 27 are dished, so that a water-receiving chamber is formed between them. The inner member 25 forms a rest for the inner portions of the fingers and the forward portion of the palm of the operating hand, as indicated by Figure 1. The inner member 25 has a substantially circular margin, the diameter of which is such that the tips of the fingers may be flexed across the margin.

and cooperate with the thumb, also flexed across the margin, in grasping a detached applicator 29, and releasably confining it on the outer member 27, the applicator being supplied with water through orifices 30 in the outer member, said member constituting a rest for the applicator. When the hand is opened, the applicator is released and drops from the nozzle. The applicator may be a sponge, a mass of cotton waste, a bunched sheet of cheese cloth, or a body of any other suitable nature, adapted to conduct water from the rose head to the surface 18. The applicator may therefore be discarded, after it is rendered unfit for further use, and a fresh one may be substituted for it, there being no connection between the applicator and the rose head other than that provided by the operating hand.

The unobstructed circular margin of the rose head surrounds and projects outward from the portion of the neck which joins the rose head. The major axes of the receiving and rose heads are substantially parallel with each other, and said heads are spaced apart by the neck sufficiently to permit the insertion of portions of the operating hand therebetween. The neck is formed to bear on side surfaces of the fingers, while the back of the rose head is formed to bear on the forward portion of the palm and on inner surfaces of the fingers adjacent to the palm. The unobstructed margin of the rose head permits inward flexure of the outer portions of the fingers and of the thumb, as shown by Figure 1. The neck is joined to the outer end portion of the receiving head 12, so that when the washer is operatively held, the receiving head is offset inwardly from the outer portions of the flexed fingers and is located in a non-interfering position relative to a body being washed, as shown by Figure 1. This is true, generally speaking, whether the receiving head 12 is provided with the nozzle portion 15, as shown by Figures 1 and 3, or is not provided with said portion, as shown by Figure 5.

When the washer is used on a reentrant or recessed surface, there may be some liability of contact between the outer end portion of the receiving head and a portion of said surface, not existing when the surface is substantially flat. I therefore provide the nozzle portion 15 with a cap 32, covering the external surfaces of the nozzle portion and composed of soft rubber, so that it constitutes a buffer adapted to prevent injurious contact of the nozzle portion with a surface being washed. Said cap is adapted to be turned on the nozzle portion and is provided with an outlet 33, formed like the outlet 16, and adapted to register therewith when the cap is turned to one position, the cap, when turned to another position, closing the outlet 16.

In practice, an intermediate finger as the second finger of the operating hand may be inserted in the opening 24, the adjacent fingers bearing on the external surfaces of the neck, as shown by dotted lines in Figure 4, so that the intermediate and adjacent fingers bear simultaneously on the neck and prevent a turning movement of the washer in the hand.

As shown by Figure 5, the nozzle portion 25 may be omitted, so that the head 12 communicates only with the neck duct. The device shown by Figure 5, is useful as a bath-room appliance, enabling the user to apply the applicator to body surfaces and to surfaces of a bath-tub to clean the latter.

The illustrated form of the receiving head 12, the body member 20 of the neck, the groove 21, and the inner member 25 of the rose head, is such that these parts may be formed as a single integral die casting, the passages 23 and 26 being formed by drilling, before the closing member 22 and the outer member 27 of the rose head are applied.

The metal employed may be aluminum, and the annular closing member 22 and the outer rose head member 27 may be of the same metal, and may be secured by aluminum solder forming water-tight joints.

The invention may be otherwise embodied, for example, as shown by Figures 6 and 7, in which the receiving head is composed of a circular portion 35, constituting the outer end of the head, and a tubular portion 37, constituting the inner end of the head, and adapted to engage a base. The portion 35 is provided at one side with a jet-emitting outlet 36. The water-conducting neck 38 connecting the receiving head with the inner member 39 of the rose head, may be straight and oblong in cross section, and formed to be interposed between only two fingers of the operating hand. The outer member 40 of the rose head may be secured to the inner member 39, in any suitable way.

The water-conducting neck may be otherwise formed, as shown by Figures 9 and 10, so that it does not extend between fingers of the operating hand. In these figures the neck, designated by 20^a is a water-conducting loop or bridge forming a portion of the wall of an opening 21^a, adapted to receive all of the fingers of the operating hand, the opening being completed by the inner member 25 of the rose head.

While, as hereinbefore described, the delivery head is shown as having the form of a rose head, and this particular form is a preferable one, it will be evident that the invention is not necessarily limited to making the delivery head of this exact form, that is circular in outline. Many of the advantages of the improved article will be attained if the delivery head is of slightly different

form from that illustrated, it only being necessary that such head shall provide a chamber having a delivering face adapted to suitably support the applicator and supply water thereto.

I claim:

1. A surface washer comprising a water-conducting receiving head, a water-delivering head, and a water-conducting neck, extending substantially at right angles to the plane of the delivering head, directly connecting the heads and spacing the same apart, the neck and delivering head being formed to be grasped by an operating hand and permit the flexure of fingers and the thumb across the delivering face of said head to confine a detached applicator thereon, the arrangement being such that the receiving head is offset inwardly from the outer portions of the flexed fingers when the washer is in use, so that said head is in a non-interfering position relative to the surface to which the applicator is applied, said receiving head including an outwardly directed nozzle adapted to emit a jet of water beside the back of the operating hand without contact therewith.

2. A surface washer as specified by claim 1, the receiving head including an outwardly directed nozzle adapted to emit a jet of

water beside the back of the operating hand without contact therewith, and provided with a soft rubber cap rotatable on the nozzle and constituting a buffer and a valve whereby the nozzle may be opened and closed.

3. A three-piece surface washer comprising a water-conducting receiving head of cast metal; a water-conducting neck composed of a grooved body member, cast integral with the receiving head, and a separately formed outer member covering the groove and having a water-tight connection with the body member; and a delivering head composed of a back member, cast integral with the body member of the neck, and a separately formed perforated front member having a water-tight connection with the back member and forming therewith a water chamber communicating with the neck, the receiving head, the body member of the neck, and the back member of the delivering head, constituting one of the pieces, while the outer members of the neck and delivering head constitute the other pieces.

In testimony whereof I have affixed my signature.

FRED G. STONE.
